DESIGN FOR A COMPRESSOR MEMBER FOR A PAPER FASTENER

Clarence W. Morse, Santa Monica, Calif.

Application March 13, 1943, Serial No. 109,746

Term of patent 14 years

To all whom it may concern:

Be it known that I, Clarence W. Morse, a citizen of the United States, residing in Santa Monica, in the county of Los Angeles and State of California, have invented a new, original, and ornamental Design for a Compressor Member for a Paper Fastener, of which the following is a specification, reference being had to the accompanying drawing, forming part thereof.

Fig. 1 is a face view of a compressor member for a paper fastener, showing my new design.

Fig. 2 is an end view of said compressor member for a paper fastener.

Fig. 3 is a side view of my compressor member for a paper fastener.

Fig. 4 is an enlarged broken section taken along line 4—4 of Fig. 1.

Fig. 5 is an enlarged transverse section taken along line 5—5 of Fig. 1.

I claim:

The ornamental design for a compressor member for a paper fastener, substantially as shown.

CLARENCE W. MORSE.
